Primary Examiner — Andrew Kerr*Assistant Examiner* — Chariton Alexakis(74) Attorney, Agent, or Firm — Schmeiser, Olsen & Watts, LLP(57) CLAIM

The ornamental design for combined cutting board and bookstand, as shown and described.

DESCRIPTION

FIG. 1 is a perspective view of a combined cutting board and bookstand, showing my new design;

FIG. 2 is a front elevation view thereof;

FIG. 3 is a right-side elevation view thereof;

FIG. 4 is a left-side elevation view thereof;

FIG. 5 is a top plan view thereof;

FIG. 6 is a bottom plan view thereof; and,

FIG. 7 is a rear elevation view thereof.

The broken lines form no part of the claimed design.

1 Claim, 6 Drawing Sheets(56)
